PUMP

Leonidas Coyle, Trenton, N. J.

Application October 3, 1932, Serial No. 635,899

3 Claims. (Cl. 103—188)

This invention relates to a pump and, more particularly, to that class of pump which is designed to be carried by an operator who also transports a supply of liquid for the purpose of fire fighting, 5 tree or plant spraying, etc.

It has for an object to provide certain improvements whereby, during operation, the ejection of liquid is very forcible and substantially continuous rather than spasmodic.

10 Another object consists in providing certain improvements whereby, during operation, air is trapped and held in the pump, unaffected by the position of the pump, so that a substantially constant nozzle pressure is provided and the liquid is ejected in a substantially continuous and nearly uniform stream.

Another object consists in providing certain improvements whereby the pump may be operated with the hand that grasps the end thereof which 20 is away from the nozzle, usually the right hand, with the result that the operation is more facile and swaying of the nozzle or ejection end, with consequent inaccuracy of stream direction, is avoided.

25 Another object consists in providing certain improvements whereby seepage of the liquid from the source of supply into and through the pump, when out of use, is avoided.

Another object consists in providing certain 30 improvements in the form, construction and arrangement of the several parts, whereby the above named and other objects may effectively be obtained.

A practical embodiment of the invention is represented in the accompanying drawing, in which

Fig. 1 represents a side elevation of the pump, the parts being shown in different positions in full and in dotted and in dash-and-dotted lines;

Fig. 2 represents a broken side view, partly in 40 section, on an enlarged scale;

Fig. 3 represents a broken longitudinal section on the same scale as Fig. 2;

Fig. 4 represents a transverse section taken in the plane of the line IV—IV of Fig. 3, looking in 45 the direction of the arrows;

Fig. 5 represents a transverse section taken in the plane of the line V—V of Fig. 3, looking in the direction of the arrows; and

Fig. 6 represents a transverse section taken in 50 the plane of the line VI—VI of Fig. 3, looking in the direction of the arrows.

The pump comprises an intake nipple denoted by 1, which may be of any well known or approved form, and which is intended to be connected by a 55 hose, or the like, shown in Fig. 1, with a source of

liquid supply, not shown. Such a source of supply may, for instance, consist of a tank of several gallons capacity arranged to be supported on the back of the operator. A tank of this kind is in common use in connection with the care of forest preserves, and it may contain water for the quenching of incipient fires or a chemical for exterminating vermin, or other desired liquid. 5

The nipple 1 is fitted to be threaded on the butt-piece 2 that has ports 3 which are opened 10 and closed during the operation of the pump by the action of a valve 4 that is freely mounted on the stem of a screw 5 which is threaded into the butt-piece 2 intermediate the ports 3. A cylinder 6 which may, for instance, be composed of drawn 15 tubular metal is threaded onto the butt-piece 2 at one end, and its opposite end is threaded onto a sleeve 7. A portion of the cylinder 6, adjacent the sleeve 7, is annularly indented to provide an interior shoulder 8, and a pair of washers 9, together with packing 10, are interposed between said shoulder and the adjacent end of sleeve 7. 20

A shell 11 has a sliding fit within sleeve 7, washers 9 and packing 10. Its inner end is threaded into a piston 12 located within cylinder 25 6. The said piston is provided with a series of ports 13 which are arranged to be opened and closed, during its reciprocation, by a valve 14 that is loosely mounted on screw 15 which is threaded into piston 12 centrally of ports 13. 30

The other end of shell 11 is threaded into a cap 15 at the front or ejection end of the pump.

A tube 16 is located within shell 11 and held in spaced relation thereto by spacing rings 17, 18 located adjacent the inner and outer ends 35 respectively. These parts may be secured together by a friction engagement, or by brazing, or in any other desired manner.

A series of radially disposed ports 19 formed in the tube 16 intermediate its ends opens communication between the interior of said tube and the annular space between the tube and shell 11. 40

A suitable nozzle 20 is threaded onto cap 15, and its engagement therewith made water tight by a washer 21. 45

In operation, and assuming the apparatus to be used by a forest preserve fire fighter, the nipple 1 is connected by hose to a tank carried on the back of the operator. The hose is long enough to permit the pump to be held in the hands in front of the operator. When the latter desires to eject the liquid, he seizes the cylinder 6 with one hand and the shell 11 with another, and reciprocates the parts by moving the cylinder. The hand on the shell 11 serves to guide the stream. The in- 50 55

active position of the parts when out of use, is represented in Fig. 2 and in dotted lines in Fig. 1, so that the first movement of reciprocation is to move the cylinder 6 away from shell 11 as indicated in Fig. 3. This forms a partial vacuum within the cylinder 6 at the rear of piston 12, which vacuum opens valve 4 and causes fluid to be sucked in through the hose and nipple 1 from the tank, not shown. At this stage valve 14 is, of course, closed by the partial vacuum.

In the reverse movement of the parts, the compression of the liquid within cylinder 6 closes valve 4 and opens valve 14. This causes the liquid to pass from cylinder 6 into tube 16 and be ejected through nozzle 20. A part of the liquid compressed within tube 16 at this stage escapes through ports 19 into the annular space between tube 16 and shell 11, which escaping liquid compresses the air located in said annular space. When the parts are again moved so as to draw in an additional supply of liquid from the tank, which movement naturally relieves the pressure within tube 16 and would ordinarily cause an interruption in ejection of fluid from the nozzle, the air that has been compressed in the annular space between tube 16 and shell 11 forces the liquid therein back through ports 19 into tube 16 and ejects the same through the nozzle, thereby preventing an interruption in ejection.

It will be understood that the parts are intended to be operated with reasonable rapidity so that there is only a short interval between the ejection strokes, and I have found that the action of the compressed air in the space between tube 16 and shell 11 is sufficient to compensate for the said interval and to maintain, with substantial uniformity, a continuous ejection stream. This is a particular advantage in fighting incipient fires and is an advantage from the point of view of economy of time and effort in all situations. Not only is the stream continuous, but it is very powerful and it has been found that, in actual trial, the stream may be ejected to an extraordinary distance for a device of this character.

When the parts are in the idle position indicated in Fig. 2 of the drawing, it will be observed that the piston 12 abuts valve 4 and holds it against ports 3. This prevents seepage of the liquid from the tank through the pump and the loss thereof. The avoidance of such seepage is of importance from the point of view of convenience to the operator and also from the point of view of conserving the supply of liquid which is necessarily limited in the case of a tank carried by an operator.

It will be understood that various changes may

be resorted to in the form, construction and arrangement of the several parts without departing from the spirit and scope of my invention; and hence I do not intend to be limited to the details herein shown and described, except as they may be included in the claims.

What I claim is:

1. A device of the character described comprising, a cylinder, a piston fitted to reciprocate in the cylinder, a tubular shell connected to the piston, a nozzle connected to the shell, a tube within the shell connected to the piston and the nozzle and spaced from the shell so as to form a chamber between it and the shell, ports intermediate the ends of the tube opening communication to the chamber, said ports being sufficiently removed from the ends of said tube to provide an air chamber of relatively large volume selectively at either end thereof dependent on the position of the device, and a valve in the piston for intermittently opening communication between the cylinder and the tube, whereby liquid may be forced from the cylinder into the tube and through the ports into said chamber against the confined air therein during an ejection movement and ejected from the chamber through the ports into the tube and through the nozzle by said confined air during a suction movement of the members.

2. A device of the character described comprising, reciprocable members, a nozzle port on one of said reciprocable members, a storage chamber carried by said nozzle-ported reciprocable member, and a communicating passageway between said storage chamber and said nozzle-ported reciprocable member, said passageway being sufficiently removed from the ends of said chamber to provide an air chamber of relatively large volume selectively at either end thereof dependent on the position of the device.

3. A device of the character described comprising, two reciprocable members, a nozzle port on one of said reciprocable members, a storage chamber carried by said nozzle-ported reciprocable member, a communicating passageway between said storage chamber and said nozzle-ported reciprocable member, said passageway being sufficiently removed from the ends of said chamber to provide an air chamber of relatively large volume selectively at either end thereof dependent on the position of the device, a suction port in the other of said reciprocable members, a check valve positioned at said suction port, and means on the other of said reciprocable members for holding said check valve closed.

LEONIDAS COYLE.
